Patented July 10, 1917.

UNITED STATES PATENT OFFICE.

IRA YELTON AND RAYMOND C. SIRY, OF GRANTS LICK, KENTUCKY.

LOCKING DEVICE FOR AUTOMOBILES.

1,232,746.

Specification of Letters Patent. Patented July 10, 1917.

Application filed March 26, 1917. Serial No. 157,550.

To all whom it may concern:

Be it known that IRA YELTON and RAYMOND C. SIRY, citizens of the United States, residing at Grants Lick, in the county of 5 Campbell and State of Kentucky, have invented certain new and useful Improvements in Locking Devices for Automobiles, of which the following is a specification, reference being had to the accompanying drawings.

This invention relates to automobile attachments, and particularly to means for locking automobiles to prevent their being stolen or used, without authority.

15 The general object of the invention is to provide a very simple, cheaply constructed, and easily applied device for the above stated purpose, which will prevent the steering mechanism from being used while the 20 locking device is in applied position, and a further object in this connection is to provide means for also locking the starting crank.

A further object is to provide a device of 25 this character so constructed that it does not have to be removed from the machine in order to permit the machine to be steered and operated.

Other objects will appear in the course of 30 the following description.

The invention is illustrated in the accompanying drawings, in which:—

Figure 1 is a side elevation of an automobile locking device constructed in accordance with our invention, the axle and steering rod being shown in section;

Fig. 2 is a top plan view of our device;

Fig. 3 is a longitudinal sectional view thereof;

40 Fig. 4 is a vertical sectional view thereof, the member 25 and the sector gear 22 being in elevation;

Fig. 5 is a section on the line 5—5 of Fig. 3.

45 The device, as illustrated in Fig. 2, consists of a block or a body 10 having a relatively thick head 11 at one end, this head being longitudinally slotted parallel to the face of the body, as at 12, and this slot being of sufficient width to permit the connecting or steering rod, which connects the steering knuckles, to be inserted in the slot and moved freely therein. The end of the slot 12 is closed by a removable block 13, whose inner face is concavely rounded, as at 14. This block may be held in place in any

suitable manner, so that it cannot be readily removed. The opposite end of the body 10 from the head 11 is longitudinally slotted as at 15, and operating in this slot is a rack 60 bar 16, having teeth 17 upon one face. This rack bar constitutes a plunger rod and is angularly bent, as at 18, and extends downward, and is then again angularly bent to provide a plunger 19, which extends through 65 a passage 20 formed in the front wall of the head 11. It will be understood that the plunger is reciprocable in the opening 20 toward and from the rear wall formed by the block 13. Formed upon the upper face 70 of the body 10, on each side of the slot 15, are the ears 21, and mounted between these ears is a sector-gear 22 having trunnions 23 which pass into the ears 21. These trunnions may be formed by a pin driven 75 through the bearings 23 and through the member 22. This sector gear 22 has an arm 24 extending radially therefrom, this arm at its extremity being formed with a laterally disposed jaw 25 and a portion 26 of an opposed jaw. Pivoted to the portion 26 is a section 27, which completes the jaw opposed to the jaw 25, this jaw section 27 being formed with a forwardly extending lug 28. This lug 28 and the forward end of the jaw 85 25 are adapted to lie flat against each other and are formed with transverse perforations 29, for the reception of the hasp of a padlock 30.

In order to attach the body 10 to the 90 front axle of the automobile, I provide the downwardly extending stud bolts 31, which may be formed with the body 10 on each side of the slot 15, these stud bolts being screw-threaded at their outer ends for engagement with nuts 32, and mounted upon each pair of stud bolts is a longitudinally extending bar 33 adapted to extend beneath and clamp against the under face of an axle. The under face of the body 10 on 95 each side of the slot is slightly recessed, as at 34, to provide for engagement with the upper face of the axle.

It will be noted that the arm 25 is formed on its under face with a stop lug 35, which 105 abuts against the end of the rack bar 16 when the rack bar is jammed against the connecting rod 36 and this takes the strain from the teeth 17 when the rack bar 16 is locked. It will also be noted from Fig. 2 110 110 that the ears 21 are cut away as at 37 in order to allow the arm 24 to lie flat on the

upper face of the body 10 when shifted rearward.

In the practical use of this invention, the block 13 is removed and the connecting rod 36, connecting the steering knuckles of the automobile, is disposed within the slot 12. The block 13 is then replaced and engaged with the body 10. When it is desired to lock the machine, the arm 24 is rotated toward the front of the machine in a position to engage with the starting crank 37. This rotation of the arm 24 causes the rack 16 and the plunger 19 to move rearward and bind against the connecting rod 36, holding this steering rod or connecting rod from longitudinal movement, and thus absolutely locking the steering mechanism of the car. Furthermore, the jaws 25 and 27 embrace the starting crank and are locked by the padlock 30 and, under these circumstances, the starting crank cannot be turned to start the machine. It is to be understood that the crank is to be pushed in against the crank shaft and turned straight down in order to lock it within the jaws 26 and 27. When the device is unlocked, the arm 24 is shifted rearward, so as to lie upon the upper face of the body 10 and this retracts the plunger and releases the steering rod which may then be reciprocated through the slot 12, without difficulty. It will be seen that this device makes it impossible to start the engine or even guide the car when it is locked and will thus render impossible, the stealing of cars or the unauthorized use of cars. The device is very simple, can be easily applied to any automobile of ordinary make, and is thoroughly effective in action.

Having thus described the invention, what is claimed is:

1. A locking device for motor cars, comprising a body adapted to be attached to the front axle of a motor car, the body being formed to receive the steering rod of the car, a plunger shiftable through the body into engagement with the steering rod to prevent its movement, and means for locking the plunger in its applied position.

2. A locking device for motor cars comprising a body operatively mounted upon the motor car, the body being formed to receive the steering rod of the car, a plunger shiftable through the body into engagement with the steering rod to prevent its movement, a sector gear operatively engaging the plunger to shift it and having an arm formed with jaws adapted to embrace the crank of an automobile, and means for locking the jaws in their closed position.

3. A locking device for motor cars adapted to be operatively attached to the motor car, said body being longitudinally slotted for the reception of the steering rod and provided with a removable block closing the rear end of the slot, a plunger shiftable

through the body and into said slot and into engagement with the steering rod to prevent its movement, and means for locking the plunger in applied position.

4. A locking device for automobiles comprising a body having a transversely extending slot extending inward from the rear end of the body and adapted to receive the steering rod of an automobile, a block detachably engaged in said slot and closing the rear end thereof, a plunger extending through the forward wall of the body and into said slot, the plunger having an upwardly extending shank, said shank being then extended horizontally and provided upon its upper face with gear teeth, the forward end of the body being slotted to receive and guide the forward end of the said shank, there being ears on each side of the slot, a sector gear rotatably mounted in said ears and engaging the teeth of the shank and having a radially extending arm, the extremity of the arm being formed with a fixed jaw, and a pivoted jaw adapted to embrace the starting crank of the automobile, and means for locking the said jaws.

5. A locking device for automobiles comprising a body having a transversely extending slot extending inward from the rear end of the body and adapted to receive the steering rod of an automobile, a block detachably engaged in the slot and closing the rear end thereof, a plunger extending through the forward wall of the body and into said slot, the shank of the plunger being provided upon one face with gear teeth, the forward end of the body being slotted to receive and guide the forward end of the shank, a sector gear rotatably mounted on the forward end of the body and being provided with teeth engaging the shank and having a radially extending arm, said arm being formed with a lug upon its under face adapted to abut against the forward end of the body when the arm is turned to a horizontal position, and clamping means formed upon the forward end of the arm.

6. A locking device for automobiles comprising a body adapted to be attached to the front axle of a motor car and formed to receive the steering rod of the car, a plunger shiftable through the body into engagement with the steering rod to prevent the movement of the latter, an arm pivoted upon the body and operatively engaged with the plunger to cause its longitudinal movement when the arm is rotated in one direction, and means carried by the arm for locking engagement with a part of the automobile.

7. A locking device for automobiles comprising a body having a plurality of pairs of downwardly extending bolts adapted to be disposed in each side of the axle of the automobile, transversely extending clamping bars mounted upon said bolts, said body

being formed to receive the steering rod of a car, a plunger shiftable through the body into engagement with the steering rod to prevent its movement, means for shifting 5 said plunger, and means for locking the shifting means when the plunger is in its clamping position.

8. In an automobile, a steering rod and a starting crank, and means for locking the 10 steering rod from movement and shiftable into or out of operative position, means for shifting said locking means, said last named

means being adapted to engage the starting crank and being locked thereon when the first named means is shifted into engagement with the steering rod. 15

In testimony whereof we hereunto affix our signatures in the presence of two witnesses.
